UNITED STATES PATENT OFFICE.

MICHAEL ALTMAN, OF CHICAGO, ILLINOIS.

DESIGN FOR A MENU-CARD.

No. 39,912.

Specification for Design.

Patented April 13, 1909.

Application filed October 17, 1908. Serial No. 458,325. Term of patent 7 years.

To all whom it may concern:

Be it known that I, MICHAEL ALTMAN, a citizen of the United States, residing at Chicago, in the county of Cook and State of Illinois, have invented a new, original, and ornamental Design for Menu-Cards, of which the following is a specification, reference being had to the accompanying drawing, forming part thereof.

The figure is an elevation of the menu card showing my new design.

I claim—

The ornamental design for a menu card as shown.

MICHAEL ALTMAN.
